TIME AND PRODUCTION RECORDER

Peter A. Cooney, Chicago, Ill., assignor to Chrono-type Corporation, Chicago, Ill., a corporation of Illinois

Substituted for abandoned application Serial No. 352,282, August 12, 1940. This application February 22, 1943, Serial No. 476,784

12 Claims. (Cl. 234—5.8)

This invention relates in general to a combined electrical and mechanical apparatus for printing a visible record of every deviation from an established standard production or performance of another machine or producing unit to which this apparatus is applied, and thereby comprising a time study analysis or comparison of the operation of that unit to the established performance expected of it.

An important object of the invention is in the provision of a simple apparatus mechanism or equipment of this kind which may be readily applied to producing units for various types of manufacture such as printing presses, punch presses and other automatic or repetitive equipment such as used for example in the manufacture of tin cans, metal caps, paper manufacturing, and the like.

A further object of the invention is in the provision of an improved apparatus of this kind by which the operation of a producing unit may be obtained continuously from the location of the unit itself, but with the result appearing at a distance, as in the office of the superintendent or a supervisor, where the operation of that unit may be observed.

A still further object of the invention is in the provision of means accessible and operated by the attendant of a producing unit to which this apparatus is applied for indicating and recording any one of a number of reasons for lack of production which is apparent upon examination by the supervisor at a distance from the producing unit.

A still further object of the invention is in the provision of an apparatus of this kind in which a tape record is produced which indicates production above or below an established standard, recorded at intervals together with means operated by a producing unit attendant for indicating the cause for any delay.

A still further object of the invention is in the provision of a mechanical cost accounting system based on the time study which compares actual production with the standard and produces a visible record of production of a producing unit which enables a complete analysis to be made periodically of the performance of the unit to which this apparatus is applied, accessible to a supervisor at the time the record is made, and not days or hours thereafter, so that a correction and improvement can be made while the work is in progress.

Other objects of the invention will appear in

the specification and will be apparent from the accompanying drawings in which,

Fig. 1 is a perspective view illustrating the apparatus provided for use by a workman at a producing unit, and also the recording apparatus which is located in a supervisory or a foreman's office; Fig. 2 shows a piece of tape with a printed record thereon, indicating the operation of a producing unit; Fig. 3 is a plan view of some of the mechanism used in printing and recording the record on the tape; Fig. 4 is a detail of the clutch operating mechanism; Fig. 5 is a detail of the tape printing mechanism; and Fig. 6 is a wiring diagram and a diagrammatic view of the connection and operation of the parts.

In operating this apparatus, a switch is located near each producing unit or machine to be tested, and is connected by an electric circuit to a recording and tape feeding mechanism located in the foreman's office. A suitable switch in connection with the producing unit opens and closes each time a piece is finished or an operation is finished by the unit. This sends an electric impulse into the remote recording unit which operates the mechanism.

Time and production wheels or dials are set in motion in the recording mechanism by which a certain established or standard production is expected within a certain interval of time. If the predetermined amount of work is actually produced within the set time, quantity production is perfect. If the standard production is not obtained in the time, an EX is printed on the tape indicating that excess time is consumed, but should the operator produce at a faster rate than the standard, the production dial will be ahead of the timing dial and a credit CR symbol will be printed.

In practice, production is figured for every tenth of an hour so that for eight working hours, there will be eighty time intervals, but the time is purely arbitrary as any desired interval may elapse. The net result of actual performance is thus compared to the standard performance and is recorded upon a tape in the office of the supervisor, who after the appearance of the first few EX's, can go to the particular producing unit to ascertain and correct the cause of the delay.

An important object of the tape record is that it affords an analysis of idle time. Frequently machines are idle or are forced to stop for reasons beyond the control of the operator. By providing a series of code numbers, the causes for such idle periods are shown on the tape. For example, in the printing industry, the following num-

bers may be used: 1—make ready, 2—changes on form, 3—color wash up, 4—wait for material, 5—feeder trouble, 6—form trouble, 7—repairs, 8—paper lift period, 9—general wash up, and 10—no work.

These or additional causes may also be listed, and for each different industry or machine to which this apparatus is applied, a different set of reasons or causes is used. Code members may be printed on the tape in the same column, or in different columns to indicate which causes are chargeable against the operator, the machine, or the management.

When such delays occur, the operator dials the number representing the cause and this number is printed on the tape, the time recorder showing the duration of such delays. A dial, such as an automatic telephone dial, is mounted at each machine by which the operator can report and record on the tape in the supervisor's office the cause for any delay in a few seconds.

Referring now more particularly to the drawings, the apparatus comprises an operator's signal box 12, which is located adjacent the producing unit which is being tested and a tape discharging and recording unit 13, usually located in the superintendent's or supervisor's office. These parts are connected by electric conductors 14. The recording unit has an electrical plug-in connector 15 for supplying current thereto, and the signal box has an electrical plug-in connector 16 for connecting it to a suitable switch or counting device on the machine being tested.

In the face of the signal box is an arm or pointer 17, movable over a graduated dial with points designating the delay code numbers as from 1 to 10. This pointer may be operated or set by a separate knob 18 with a knob 19 which may be pressed to close a switch 21 when the pointer is set at any desired point, this entire mechanism being represented as an automatic telephone dial 20 in Fig. 6 with a separate manually closable switch 21.

Operation or setting of the cause pointer arm 17 by the machine operator energizes and correspondingly steps a cause advance relay 22 located in the tape discharge and recording unit 13 to set up a prearranged code number, as from 1 to 10, which indicates the cause for delay. Likewise, the manual closing of switch 21 actuates a cause printing relay 23 which is also located in the recording unit 13, so that the delay cause, set up at the operator's signal box is reproduced and recorded upon a tape 24 automatically discharged from the recording unit.

Assuming that current is supplied to conductor mains 25 and 26, a circuit is traced through the cause advance relay from main conductor 26 through conductor 27, pointer arm 17, cause indicator dial contacts 28, conductor 29 and cause advance relay 22 to the other supply main 25. Likewise, a circuit is traced from main 26 through switch 21, conductor 29, cause printing relay 23, to the other supply main 25.

In the tape discharging and recording unit, there is a rotatable time disk 30 and a rotatable production disk 31, the former operated by a synchronous motor 32 and the latter operated through a reduced driving gear connection 33, with a pawl 34 and ratchet wheel 35 connector, operated by a production coil or relay 36. This production coil is connected through a switch 37, actuated by a suitable cam or counter arm 38, usually located on the producing unit under test and operative to close the switch 37 for

each operation of the unit. A circuit for this production coil is traced from conductor 26 through switch 37, conductor 39, production coil 36 to the opposite current supply main 25. Each operation of the production coil produces a movement of the pawl 34 and its ratchet wheel 35 which is communicated to the production disk 31.

Projecting from the time disk 30 are contact pins 40 and 41 adapted to engage switch spring fingers 42 and 43 respectively in the starting position of the disk for closing a switch with the first finger 42 and for opening a switch with the other finger 43. When this disk is driven a predetermined distance in the direction of the arrow, foremost contact pin 41 engages a spring contact finger 44 to close a circuit with the spring finger 45 and continues until the latter engages a contact finger 46.

Likewise, the production disk 31 which is represented as driven by the driving connection 33, has projecting contact pins 50 and 51 which engage spring fingers 52 and 53 respectively for closing and opening switch connections with contacts 54 and 55. As this disk is driven in the direction of the arrow, the foremost contact pin engages a spring finger 56 which forms an electrical connection with a spring finger 57 and the latter with a contact finger 58.

In their zero positions, the time disk 30 and the production disk 31 are held against movement by a time locking clutch coil 60 and a production locking clutch coil 61 respectively, these coils controlling and operating yokes 63 and 62, movably engaging clutch collars 65 and 64 respectively for holding them out of driving engagement with disks 30 and 31 against the pressure of clutch springs 67 and 68. The result is that when these coils are energized, the clutches are drawn out of driving engagement but as soon as the circuit is broken by opening machine switch 37, the clutches are forced in by the springs 67 and 68 and the disks 30 and 31 are driven competitively for a predetermined time and production.

The holding circuit is traced from supply main 26 through machine and contact switch 37, conductor 39, conductor 68, switch finger 42, contact finger 69, conductor 70, contact finger 54, switch finger 52, conductor 71 to production coil 61 and time coil 60 in parallel, thence through conductor 72 to the opposite supply main 25. At the beginning of their operation, the disks 30 and 31 move away from their zero position together when switch 37 is opened, thereby opening the switch fingers 42 and 52 in the above circuit which is not re-established until the disks reach their outer driven or limiting position, are released from their clutches and are returned to zero position. Each disk is driven in the direction indicated by the arrow against the tension of a returning spring 73 which tends to return the disk to zero position but cannot do so against the action of the clutch springs 67 and 68.

If the time disc is first returned to its starting position, the other disc 31 will continue to be driven by its clutch connection until it too reaches its limiting position whereupon it will be released as hereinafter described, returned to its starting position by spring 73 and the EX time will be printed on the tape after the six minutes time. In the same manner, if the production disc 31 reaches the end of its path of travel before the time disc, a CR designation and the time will be printed on the tape, and the time disc 75 will continue its movement until it reaches the

predetermined time limit, whereupon its clutch collar 65 will be released from driving engagement therewith, it will return to starting position and the time thereof will be printed.

When the time disk or the production disk reaches its limiting position which may be reached, for example, in six minutes by the time disk or in a corresponding standard production, indicated by the production disk, the foremost contact pin 41 or 51 reaches the contact finger 44 or 56, and first closes the circuit with the time printing and tape advance relay 75 which is as follows:

From circuit main 26 through conductor 76 and contact fingers 44 and 45, or through contact fingers 56 and 57 to conductors 77 and thence to one side of the relay 75 and from the other side of the relay to the opposite current supply main 25.

This relay 75 thereupon automatically prints the time on the tape 24 and the tape is advanced one step ready for the next printing.

This movement of either disk 30 or 31 also causes the engagement of fingers 45 and 46 or 57 and 58 and completing a circuit thereby through a time release clutch magnet 80 or a production release clutch magnet 81, depending upon which disk and therefore which pair of contacts are first engaged.

If the time clutch contacts 45 and 46 are first engaged, a circuit is closed from the current supply main 26 through conductor 76 and spring fingers 44, 45 and 46, then through conductor 82 and 83 to time release magnet 80 and thence to circuit main 25. If the production contacts are first closed, a circuit is traced from circuit main 26, conductor 76, contact fingers 56, 57, 58, conductors 84 and 85 to production magnet 81 and thence to the other circuit main 25.

These release magnets 80 and 81 are operative in effect to disengage the clutch members 65 and 64 from the corresponding disks 30 and 31 as diagrammatically or conventionally represented in Figs. 3 and 6. Pivoted armatures 87 and 86 have wedging extremities and are movable by the relays 80 and 81 respectively, the said extremities being inserted between the discs 30 and 31 and their clutch collars 65 and 64 when the relays are energized to separate them from the driving engagement into which they are urged by their springs 67 and 66 respectively.

Even after the operating current to the magnets 80 and 81 is cut off, the wedging extremities of the armatures 87 and 86 are retained in their separating positions by the pressure of the corresponding clutch springs 67 and 66 until both disks 30 and 31 return to zero position. When the clutch coils 60 and 61 are then momentarily energized at the same time, the release armatures 87 and 86 are freed from frictional contact with the clutch members allowing the driving connections of the clutch members with the disks 30 and 31 to be restored.

The effect of such release is to disengage the disk 30 or 31 from its clutch driving engagement to place it under the influence of its spring 73 which returns the disk quickly to its zero position.

If the time disk first reaches its limiting position, it means that production is not up to the expected standard and if the production disk first reaches its limiting position, it means that the actual production has exceeded the expected standard. In the first case, a circuit is traced

from current main 28 through conductor 78, spring fingers 44, 45, 46, conductors 82 and 88, contact fingers 53 and 55, conductor 89, EX printing relay 90 to the other conductor main 25.

6 The contact fingers 53 and 55 will be closed in this case because the production disk and its pin 51 have not returned to zero. In the other condition, the circuit is closed from conductor main 26 through conductor 76, spring fingers 56, 57 and 58, conductors 84 and 81, spring fingers 43, 92 and conductor 93 to CR printing coil or relay 94 and thence to the other current main 25. In this case, the conductors 43 and 92 will be closed because the time disk has not yet returned to zero position to separate them by the engagement of contact pin 41.

As soon as the time disk is returned to zero, contacts 43 and 92 are separated by pin 41 which prevents the CR relay from printing, and similarly, the return of the production disk to zero position separates contacts 53 and 55 by the engagement of pin 51, thereby opening the circuit to the EX relay 90.

Actual printing upon the tape may be effected by means of any time recording register in connection with printing relays 23, 94, 90 and 75 as shown in Figs. 2, 5 and 6. Since motor 32 is a synchronous motor, it may be also a clock or timing motor having a driving connection 101 with time registering mechanism 102 which has numbered wheels 103 for indicating minutes and fractions thereof, CR and EX designations, and a number wheel 106 for designating delay causes. An inking ribbon 105 is movable transversely in front of these number wheels and the other designations, being mounted on rollers 107 at the ends of the register mechanism 102 and moves between them and the record receiving tape 24.

40 Each of the relays 94, 90 and 75 has a pivoted armature (not shown) similar to armature 108 of relay 23. Armature 108 operates a printing block 104 and similar blocks 109, 110 and 111 are operated by relays 94, 90, and 75 respectively.

45 The tape 24 passes between the ribbon 105 and the blocks and each time a block is operated by the energization of its relay, the corresponding designation is imprinted on the tape. As the time printing block returns, the tape is advanced one step to the next position thereof.

In operation, it is in effect a race between time and production. The time disk is arranged to move to close its contacts 44, 45 and 46 in a predetermined time, for example, every tenth of an hour, and the production disk is connected to move for the standard production expected of it in that time, that is, every six minutes. When either the time disk or the production disk reaches its limiting position, corresponding contact fingers 44, 45 and 46 or 56, 57, 58 are closed and a circuit is closed as previously traced through the time printing and tape advancing relay. If the elapsed time contacts are reached first, the letters EX (indicating excessive time required to produce the unit) will be printed on the tape because six minutes has elapsed before the production contact is made. When the production contact is made which indicates when the quantity that should have been produced actually was produced, the production contacts close, and time is again printed on the tape, but the CR relay is not energized. If the time disk contacts are made first, then the production contact must come later and the difference between the two is the excess time consumed over the

standard production as provided for on the production disk. On the other hand, if the production comes in ahead of the allowed time, the CR relay is energized and CR will be printed on the tape because the production was finished before the allowed time of six minutes had elapsed. When both contacts are closed simultaneously, time only is printed and the tape advanced one step.

This race between time and production goes on continually all day or during the progress of a job, printing the results of actual against standard performance approximately every tenth of an hour depending of course upon the additions or subtractions of the EX's or CR's. Any stop time which must be taken out by the operator is represented by an operation number from 1 to 10 (or more) which is the code number for the designated cause and appears on the tape by the operation of the cause printing relay 23. When an operating machine is stopped, the operator or press man dials the operation number and switch 21 is closed manually which causes the corresponding code number and the time to be printed on the tape.

The joint operation of the time and production disks is resumed only when both of the disks have returned to zero position, and this takes place immediately after both of them reach their limiting positions from which they are returned by their springs 13; for if either one is not returned to zero position, corresponding contacts 42 and 69 or 52 and 54 will keep open the circuit which includes them and the time and production coils 60 and 61 which control the clutches for the corresponding disks 30 and 31.

The disks are held out of engagement with their respective clutch members 65 and 64 by the armatures 87 and 86 of the release magnets 80 and 81, until the circuit through both clutch controlling coils 60 and 61 is completed, which can only take place when both of the disks have returned to zero position, as previously set forth.

As it is desirable to print the time on the tape at which any of the delay or stop code signals are printed, an electrical connection is also closed to the time printing relay 15 by means of the switch 21 which also actuates the cause printing relay 23. The energizing circuit for the time printing relay under these circumstances is traced from conductor main 26 through switch 21, switch contact 96 normally open but closed by the switch and conductor 97 to one side of relay 15, the other side of which is connected to conductor main 25. This circuit will be open except when the switch 21 is closed and is closed at the same time that the cause printing relay 23 is energized to print one of a stop or delay code numbers.

The tape 24 is printed step by step and discharged from the unit 13 in the office of the superintendent, production manager, or any other suitable place. The particular construction and operation of the printing, time recording and tape feeding is not material to the successful operation of the invention as a variety of such means, both mechanical and electrical, might be assembled and connected for producing the desired result. Certain of the mechanical parts are shown in Figs. 3, 4 and 5 and a complete diagrammatic assembly and arrangement is shown in Fig. 6 with the electrical connections necessary for producing the desired results.

A discharged record tape is read from the bot-

tom up, 480 minutes being for an 8 hour day. In Fig. 2 are shown broken portions of a complete tape which indicates that the press was idle for 44.6 minutes for cause #10, waiting for work, which is an avoidable delay. When a job was finally assigned to the press, it required 167.7 minutes for make ready, cause #1.

In any run of a job, a number of EX's are usually shown at the start indicating, for example, that some minutes of running time are lost for slow speed. This kind of a loss should be corrected at once after the first few EX's appear, and the machine speeded up. This is indicated upon the tape by the EX indications, and the amount must be figured by deducting the difference between the time designated at any EX mark and the next time indication, in this case 219.8 minus 218.3 or 1.5 minutes. If the machine speed is greater than the expected standard, a CR notation will appear for each credit period.

The time lost on any EX notation and gained on any CR notation is recorded on the tape and may be figured by deducting any EX or CR minute from the next appearing minute notation.

The lower EX loss on the tape is therefore 1.5 minutes, and one noted CR gain is .5 of a minute. The EX losses are marked on the tape after the job is run and the tape is being examined for an analysis of the particular job. In the entire tape of the example shown, there are a number of losses and credits (of which only the ones mentioned are shown) and subtracting the CR gains from the EX losses, the net amount of time lost was 30.8 minutes.

Evidently this job was completed in a total time of 391 minutes after which there were a number of delays making up the total time for one day of 480 minutes. The 89 minutes at the top of the tape may be charged to the next job. An analysis of this as a complete job from the tape, Fig. 2 might be somewhat as follows:

	Mins.
Total time for job	391
45 Unavoidable delay, make ready	167.7 (212.3 - 44.6)
Total time left (subtract)	223.3
Avoidable loss (cause 10)	44.6 20--%
50 Available productive time	178.7
Operator's loss of time (EX's-CR's)	30.8 17.3%

Net production time
55 (subtract) 147.9 66+%

In other words, time chargeable to actual completion of the job is 147.9 minutes, the time chargeable to make ready is 167.7 and the total avoidable lost time is 75.4 minutes which is 34% of the total time of 223.3 minutes for completing the job.

With this kind of a record, it is not necessary to ask the foreman or an operator what was wrong, the tape tells that with unerring accuracy. A foreman should be able to prevent most of it as it is occurring; to speed up production if necessary, to have work ready, to prevent delay waiting for paper or material, and to enable him to decide what to do to convert this 34% loss into productive time. The tape will show an actual average production per hour much less than the normal to be expected, which should cause an investigation, resulting in the elimination of wasted time as explained. The tape

shows the conditions immediately as they occur which enables correction to be made at the start and during the continuation of a job rather than a post mortem after a long time serious loss has been sustained. This will increase efficiency not only of the machine, but also of the operator and the efficiency of the management itself. It should naturally result in better working conditions, more pay for the operator, and in the production of useful work at a less cost to the management.

While the invention has been explained more particularly as applied to a printing machine as a substitute for my application Serial No. 352,282 filed August 12, 1940, it is equally applicable to many other types of manufacture, particularly the lines that are repetitive and adapted to mass or quantity production.

I claim:

1. In a time and production recorder, movable timing means and movable means indicating production, a separate printing device actuated by one of said means to indicate the completion of a predetermined time before the completion of expected production in that time and another device actuated by said other means to indicate the completion of production in less than the predetermined time.

2. In a time and production recorder, movable timing means and movable means indicating production, a common printing device actuated by either one of said means to indicate the expiration of a predetermined time and to indicate the time when the expected production is obtained, and separate printing devices in connection with the timing and production means to indicate which of said means was first actuated.

3. In a time and production recorder, movable timing means and movable means indicating production, a separate printing device for and actuated by each of said means respectively, and a switch device in a circuit connection with each of said means for preventing the actuation of the printing device for the other means when the printing device for the first means has been actuated.

4. In a time and production recorder, movable timing means and movable means indicating production, spring means for returning either one of said movable means to a zero or starting position after a predetermined time or expected production has been reached, printing means respectively actuated by both of said movable means to indicate the expiration of a predetermined time and a predetermined production, a clutch operating device for actuating each of said movable means and a locking circuit for said clutch operating device having switches in a common circuit each closed respectively by one of the moving means at its zero position.

5. In a time and production recorder, movable timing means and movable means indicating production, a different drive including a clutch and clutch operating means for moving each of said movable means from a starting to a predetermined stop position, a switch means at the stop position of each of said movable means in circuit with a releasing relay for that movable means, a spring for returning each movable means to its starting position and switches in a series circuit with the clutch operating means and one switch being closed by each of the movable means at zero position for insuring that

both of said movable means are returned to zero position by their springs before the clutches can be reoperated to move the said movable means.

6. In a time and production recorder, a movable timing disk and a movable production disk, means for separately moving the disks from a zero to a predetermined stop position respectively, a clutch locking relay for connecting each

10 disk for such movement, clutch releasing means including a relay and a switch therefor at the stop position for each of said disks, spring means for returning each of the disks from stop to zero position when the releasing relay is operated, and 15 a time printing relay in a joint circuit with the said switches for the two disks at the stop position for indicating the time at which either of the switches is closed at one end of the movement of its respective disk.

7. In a time and production recorder, a movable timing disk and a movable production disk, means for separately moving the disks from a zero to a predetermined stop position respectively, a clutch locking relay for connecting each

25 disk for such movement, clutch releasing means including a relay and a switch therefor at a stop position for each of said disks, spring means for returning each of the disks from stop to zero position when the releasing relay is operated, a time printing relay in a common circuit with the

30 said switches for the two disks at the stop position for indicating the time at which each of the switches is closed by the movement of its respective disk, and a circuit including two switches in series, one opened by each of the respective disks at its zero position for controlling the clutch operating relays for both disks and insuring that both of the disks are at their zero position before their moving means can be again operated to drive the disks from zero to stop position.

8. In a time and production recorder, a movable time disk, a movable production disk, separate means for driving each of the disks from a starting to a predetermined stop position, a time printing and tape advancing relay included in the circuit comprising a switch at the stop position of either of said disks, and a tape actuated and the time printed thereon by said relay when either of said switches is closed.

9. In a time and production recorder, a movable timing disk and a movable production disk, means for moving each disk from a starting to a predetermined stop position, a time printing and tape advance relay for a record receiving tape, a switch at the stop position of each disk, the switches being connected in a joint circuit with the said relay for actuating it to print upon and advance a tape, a printing relay for each disk having a switch in circuit therewith at the stop position and actuated to print on a tape when the switch is closed prior to the closing of the corresponding switch by the other disk.

10. In a time and production recorder, a movable timing disk, a movable production disk, a time printing and tape advancing relay, a time excess and a production credit printing relay for the time and production disks respectively, means for separately moving the disks from a starting to a predetermined stop position, switch means at the stop position for each of the disks, one switch for each disk connected in a circuit with the time printing and tape advance relay and another switch for each disk being connected in a circuit to one of the other printing relays, each of said circuits including a switch closed when

either disk is moved from its zero position to insure operation of only one of the excess time and credit relays.

11. In a time and production recorder, a movable timing disk and a movable production disk, means for actuating the timing disk for the duration of an expected production and ratchet means for operating the production disk, including a relay and a circuit therefor including a switch actuated by the production being performed, a time printing and tape advance relay for a recording tape, switch means in connection with the disks for actuating the time printing and tape advance relay, and time excess and production credit printing relays respectively marking on a tape when the predetermined time expires before the expected production is reached and

when expected production is reached before the predetermined time.

12. In a time and production recorder, a movable time disk, a movable production disk, a time printing and tape advancing relay for a record receiving tape, a time excess and a production credit relay for also printing on the tape, means including a switch at a machine under production for controlling the operation of the production disk, a cause printing relay for printing on the tape and means including a selective switch at the machine under production for indicating any one of a number of causes for lack of production which are printed by said cause printing relay 13 on the tape.

PETER A. COONEY.
